CLAIM

The ornamental design for a truck tailgate, as shown and described.

DESCRIPTION

FIG. 1 is a top perspective view of a truck tailgate showing my design;

FIG. 2 is a side elevation view thereof, the opposing side being a mirror image of the illustrated side;

FIG. 3 is a top plan view thereof;

FIG. 4 is another perspective view thereof;

FIG. 5 is another side elevation view thereof, the opposing side being a mirror image of the illustrated side;

FIG. 6 is an end elevation view thereof;

FIG. 7 is a top plan view thereof; and,

FIG. 8 is a bottom plan view thereof.

The truck tailgate is shown mounted to a truck body (indicated in broken lines in FIGS. 1-3) that is shown for illustrative purposes only and that does not form any part of the claimed design.
